Jae-Kwang Ryu, Yongin-si (KR)

(73) **Assignee:** Samsung Display Co., Ltd., Yongin-si
(KR)

(*) **Notice:** Subject to any disclaimer, the term of this
patent is extended or adjusted under 35
U.S.C. 154(b) by 1152 days.

This patent is subject to a terminal dis-
claimer.

(57) **ABSTRACT**

A thin film deposition apparatus that can be simply applied
to produce large-sized display devices on a mass scale and
that improves manufacturing yield. The thin film deposition
apparatus includes a deposition source that discharges a
deposition material; a deposition source nozzle unit disposed
at a side of the deposition source and including a plurality of
deposition source nozzles arranged in a first direction; and a
patterning slit sheet disposed opposite to the deposition
source nozzle unit and including a plurality of patterning
slits arranged in a second direction that is perpendicular to
(Continued)

the first direction. A deposition is performed while the substrate or the thin film deposition apparatus moves relative to each other in the first direction, and the deposition source, the deposition source nozzle unit, and the patterning slit sheet are formed integrally with each other.

THIN FILM DEPOSITION APPARATUS

CROSS-REFERENCE TO RELATED
 APPLICATION

This application is a continuation of U.S. patent application Ser. No. 15/145,689, filed on May 3, 2016, which is a divisional of U.S. patent application Ser. No. 12/979,656, filed on Dec. 28, 2010, which claims the benefit of and priority to Korean Patent Application No. 10-2010-0002381, filed Jan. 11, 2010 in the Korean Intellectual Property Office, the disclosures of all of which is incorporated herein by reference.

BACKGROUND

1. Field

Aspects of the invention relate to a thin film deposition apparatus that can be simply applied to produce large-sized display devices on a mass scale and that improves manufacturing yield.

2. Description of the Related Art

Organic light-emitting display devices have a larger viewing angle, better contrast characteristics, and a faster response rate than other display devices, and thus have drawn attention as a next-generation display device. Organic light-emitting display devices generally have a stacked structure including an anode, a cathode, and an emission layer interposed between the anode and the cathode. The devices display images in color when holes and electrons, injected respectively from the anode and the cathode, recombine in the emission layer and thus light is emitted. However, it is difficult to achieve high light-emission efficiency with such a structure. Thus, intermediate layers are optionally additionally interposed between the emission layer and each of the electrodes. Examples of the intermediate layers include an electron injection layer, an electron transport layer, a hole transport layer, a hole injection layer, etc.

Also, it is practically very difficult to form fine patterns in organic thin films, such as the emission layer and the intermediate layers. Thus, the red, green, and blue light-emission efficiency varies according to the organic thin films. For these reasons, it is not easy to form an organic thin film pattern on a large substrate, such as a mother glass having a size of 5G or more, by using a conventional thin film deposition apparatus. Therefore, it is difficult to manufacture large organic light-emitting display devices having satisfactory driving voltage, current density, brightness, color purity, light-emission efficiency, life-span characteristics. As such, there is a demand for improvement in this regard.

An organic light-emitting display device includes interlayers, including an emission layer, disposed between a first electrode and a second electrode that are arranged opposite to each other. The interlayers and the first and second electrodes may be formed using a variety of methods, such as using a deposition method. When an organic light-emitting display device is manufactured by using the deposition method, a fine metal mask (FMM) having the same pattern as a thin film to be formed is disposed to closely contact a substrate, and a thin film material is deposited over the FMM in order to form the thin film having the desired pattern.

2
SUMMARY

Aspects of the present invention provide a thin film deposition apparatus that may be easily manufactured, that may be simply applied to produce large-sized display devices on a mass scale, that improves manufacturing yield and deposition efficiency.

According to an aspect of the present invention, there is provided a thin film deposition apparatus for forming a thin film on a substrate, the apparatus including: a deposition source that discharges a deposition material; a deposition source nozzle unit disposed at a side of the deposition source and including a plurality of deposition source nozzles arranged in a first direction; and a patterning slit sheet disposed opposite to the deposition source nozzle unit and including a plurality of patterning slits arranged in a second direction that is perpendicular to the first direction, wherein a deposition is performed while the substrate or the thin film deposition apparatus moves relative to each other in the first direction, and the deposition source, the deposition source nozzle unit, and the patterning slit sheet are formed integrally with each other.

According to an aspect of the invention, the deposition source and the deposition source nozzle unit, and the patterning slit sheet may be connected to each other by a connection member.

According to an aspect of the invention, the connection member may guide movement of the discharged deposition material.

According to an aspect of the invention, the connection member may seal a space between the deposition source and the deposition source nozzle unit, and the patterning slit sheet from external air.

According to an aspect of the invention, the thin film deposition apparatus may be separated from the substrate by a predetermined distance.

According to an aspect of the invention, the deposition material discharged from the thin film deposition apparatus may be continuously deposited on the substrate while the substrate or the thin film deposition apparatus is moved relative to each other in the first direction.

According to an aspect of the invention, the patterning slit sheet of the thin film deposition apparatus may be smaller than the substrate.

According to an aspect of the invention, the thin film deposition apparatus may further include a correction plate disposed between the deposition source nozzle unit and the patterning slit sheet so as to block at least some of the deposition material discharged from the deposition source.

According to an aspect of the invention, the correction plate may be disposed so that the thin film formed on the substrate may have a constant thickness on the entire substrate.

According to an aspect of the invention, the correction plate may have a height that is gradually reduced as being apart from a center portion of the patterning slit sheet.

According to an aspect of the invention, the correction plate may be formed to have a circular arc shape or a cosine curve shape.

According to an aspect of the invention, the correction plate may be formed so as to block more deposition material at the center portion of the patterning slit sheet than the deposition material blocked on end portions of the patterning slit sheet.

According to an aspect of the invention, the plurality of patterning slits may be formed to have different lengths from each other.

According to an aspect of the invention, the plurality of patterning slits may be disposed so that the thin film formed on the substrate may have a constant thickness on the entire substrate.

According to an aspect of the invention, the amounts of the deposition materials deposited on the substrate may be controlled according to the lengths of the patterning slits.

According to an aspect of the invention, the patterning slit located at the center portion of the patterning slit sheet may have a length shorter than the lengths of the patterning slits located at the end portions of the patterning slit sheet.

According to an aspect of the invention, the plurality of deposition source nozzles may be tilted at a predetermined angle.

According to an aspect of the invention, the plurality of deposition source nozzles may include deposition source nozzles arranged in two rows formed in the first direction, and the deposition source nozzles in the two rows are tilted to face each other.

According to an aspect of the invention, the plurality of deposition source nozzles may include deposition source nozzles arranged in two rows formed in the first direction, the deposition source nozzles arranged in a row located at a first side of the patterning slit sheet are arranged to face a second side of the patterning slit sheet, and the deposition source nozzles arranged in the other row located at the second side of the patterning slit sheet are arranged to face the first side of the patterning slit sheet.

According to an aspect of the invention, the deposition source may include a first deposition source that discharges a host material and a second deposition source that is disposed at a side of the first deposition source and discharges a dopant material.

According to an aspect of the invention, at least a part of the host material discharged from the first deposition source and at least a part of the dopant material discharged from the second deposition source may be mixed with each other.

According to an aspect of the invention, the first deposition source and the second deposition source may be disposed in parallel with each other in the first direction.

According to an aspect of the invention, the deposition source nozzle unit may include a first deposition source nozzle unit disposed at a side of the first deposition source and including a plurality of deposition source nozzles arranged in the first direction, and a second deposition source nozzle unit disposed at a side of the second deposition source and including a plurality of deposition source nozzles arranged in the first direction.

According to an aspect of the invention, the plurality of deposition source nozzles in each of the first deposition nozzle unit and the second deposition nozzle unit may be tilted at a predetermined angle.

According to an aspect of the invention, the deposition source nozzles in the first deposition source nozzle unit and the deposition source nozzles in the second deposition source nozzle unit may be tilted to face each other.

According to an aspect of the invention, the deposition source nozzles of the first deposition source nozzle unit and the deposition source nozzles of the second deposition source nozzle unit may be tilted in such a manner that the host material and the dopant material are mixed in a constant mixture ratio throughout the entire substrate.

According to an aspect of the invention, the first deposition source and the second deposition source may be respectively formed as linear sources.

According to an aspect of the invention, the first deposition source may be formed as a linear source, and the second deposition source may be formed as one or more point sources.

According to an aspect of the invention, the first deposition source may be a plurality of point sources, and the second deposition source may be one or more point sources, and the plurality of point sources forming the first deposition source may form a revolver.

According to an aspect of the invention, the thin film deposition apparatus may include a plurality of thin film deposition assemblies, each including the thin film deposition source, the deposition source nozzle unit, and the patterning slit sheet.

According to another aspect of the present invention, there is provided a thin film deposition apparatus for forming a thin film on a substrate, the apparatus including: the thin film deposition apparatus comprises a plurality of thin

film deposition assemblies, each of which includes: a deposition source that discharges a deposition material; a deposition source nozzle unit disposed at a side of the deposition source and including a plurality of deposition source nozzles arranged in a first direction; and a patterning slit sheet

disposed opposite to the deposition source nozzle unit and including a plurality of patterning slits arranged in a second direction perpendicular to the first direction, wherein the substrate or the thin film deposition apparatus is moved relative to each other in the first direction to perform a deposition.

According to an aspect of the invention, the deposition source, the deposition source nozzle unit, and the patterning slit sheet in each of the thin film deposition assemblies may be formed integrally with each other.

According to an aspect of the invention, the deposition source and the deposition source nozzle unit, and the patterning slit sheet in each of the thin film deposition assemblies may be connected to each other by a connection member.

According to an aspect of the invention, the connection member may guide movement of the discharged deposition material.

According to an aspect of the invention, the connection member may seal a space between the deposition source and the deposition source nozzle unit, and the patterning slit sheet.

According to an aspect of the invention, the thin film deposition apparatus may be separated from the substrate by a predetermined distance.

According to an aspect of the invention, the deposition material discharged from the thin film deposition apparatus may be continuously deposited on the substrate while the substrate or the thin film deposition apparatus is moved relative to each other in the first direction.

According to an aspect of the invention, the patterning slit sheets of the plurality of thin film deposition assemblies may be smaller than the substrate.

According to an aspect of the invention, the deposition sources of the plurality of thin film deposition assemblies may respectively contain different deposition materials.

According to an aspect of the invention, the deposition materials respectively contained in the deposition sources of the plurality of thin film deposition assemblies may be simultaneously deposited on the substrate.

According to an aspect of the invention, the number of thin film deposition assemblies may be at least three, and deposition materials respectively contained in the deposition

sources of the at least three thin film deposition assemblies may include materials for forming red, green and blue emission layers.

According to an aspect of the invention, the deposition temperatures of the deposition sources of the plurality of thin film deposition assemblies may be separately controllable.

According to an aspect of the invention, the deposition amounts of the deposition materials discharged from the deposition sources of the plurality of thin film deposition assemblies may be separately controllable.

Additional aspects and/or advantages of the invention will be set forth in part in the description which follows and, in part, will be obvious from the description, or may be learned by practice of the invention.

BRIEF DESCRIPTION OF THE DRAWINGS

These and/or other aspects and advantages of the invention will become more apparent and more readily appreciated from the following description of the embodiments, taken in conjunction with the accompanying drawings of which:

FIG. 1 is a schematic perspective view of a thin film deposition apparatus according to an embodiment of the present invention.

FIG. 2 is a schematic side view of the thin film deposition apparatus of FIG. 1, according to an embodiment of the present invention;

FIG. 3 is a schematic plan view of the thin film deposition apparatus of FIG. 1, according to an embodiment of the present invention;

FIG. 4 is a plan view of a patterning slit sheet in a thin film deposition apparatus according to another embodiment of the present invention;

FIG. 5 is a plan view of a patterning slit sheet in a thin film deposition apparatus, according to another embodiment of the present invention;

FIG. 6 is a schematic perspective view of a thin film deposition apparatus according to another embodiment of the present invention;

FIG. 7 is a graph schematically illustrating a distribution pattern of a deposition layer formed on a substrate when a deposition source nozzle is not tilted, in a thin film deposition apparatus according to an embodiment of the present invention;

FIG. 8 is a graph schematically illustrating a distribution pattern of a deposition layer formed on a substrate when a deposition source nozzle is tilted, in a thin film deposition apparatus according to an embodiment of the present invention;

FIG. 9 is a schematic perspective view of a thin film deposition apparatus according to another embodiment of the present invention;

FIG. 10 is a schematic perspective view of a thin film deposition apparatus according to another embodiment of the present invention;

FIG. 11 is a schematic perspective view of a thin film deposition apparatus according to another embodiment of the present invention;

FIG. 12 is a schematic perspective view of a thin film deposition apparatus according to another embodiment of the present invention;

FIG. 13 is a schematic perspective view of a thin film deposition apparatus according to another embodiment of the present invention; and

FIG. 14 is a cross-sectional view of an active matrix type organic light emitting display device fabricated by using a thin film deposition apparatus according to an embodiment of the present invention.

DETAILED DESCRIPTION

Reference will now be made in detail to the present embodiments of the present invention, examples of which are illustrated in the accompanying drawings, wherein like reference numerals refer to the like elements throughout. The embodiments are described below in order to explain the present invention by referring to the figures.

FIG. 1 is a schematic perspective view of a thin film deposition apparatus 100 according to an embodiment of the present invention, FIG. 2 is a schematic side view of the thin film deposition apparatus 100, and FIG. 3 is a schematic plan view of the thin film deposition apparatus 100. The thin film deposition apparatus 100 includes a deposition source 110, a deposition source nozzle unit 120, and a patterning slit sheet 150.

Although a chamber is not illustrated in FIGS. 1, 2 and 3 for convenience of explanation, all the components of the thin film deposition apparatus 100 may be disposed within a chamber that is maintained at an appropriate degree of vacuum. The chamber is maintained at an appropriate vacuum in order to allow a deposition material to move in a substantially straight line through the thin film deposition apparatus 100.

In particular, in order to deposit a deposition material 115 that is emitted from the deposition source 110 and is discharged through the deposition source nozzle unit 120 and the patterning slit sheet 150, onto a substrate 400 in a desired pattern, it is required to maintain the chamber in a high-vacuum state as in a deposition method using a fine metal mask (FMM). In addition, the temperature of the patterning slit sheet 150 has to be sufficiently lower than the temperature of the deposition source 110. In this regard, the temperature of the patterning slit sheet 150 may be about 100°C. or less. The temperature of the patterning slit sheet 150 should be sufficiently low so as to reduce thermal expansion of the patterning slit sheet 150.

The substrate 400 constitutes a target on which the deposition material 115 is to be deposited. The substrate 400 is disposed in the chamber. The substrate 400 may be a substrate for flat panel displays. A large substrate, such as a mother glass, for manufacturing a plurality of flat panel displays, may be used as the substrate 400. Other substrates may also be employed. Examples of such a substrate include a size of 5G or more, but the invention is not limited thereto.

In the current embodiment of the present invention, deposition may be performed while the substrate 400 and/or the thin film deposition apparatus 100 are moved relative to each other. In particular, in the conventional FMM deposition method, the size of the FMM has to be equal to the size of a substrate. Thus, the size of the FMM has to be increased as the substrate becomes larger. However, it is neither straightforward to manufacture a large FMM nor to extend an FMM to be accurately aligned with a pattern.

In order to overcome this problem, in the shown thin film deposition apparatus 100, deposition may be performed while the thin film deposition apparatus 100 and/or the substrate 400 are moved relative to each other. In other words, deposition may be continuously performed while the substrate 400, which is disposed to face the thin film deposition apparatus 100, is moved in a Y-axis direction. The deposition is performed in a scanning manner while the

substrate 400 moves in a direction of arrow A in FIG. 1 relative to the deposition source 110. Although the substrate 400 is illustrated as being moved in the Y-axis direction in FIG. 1 when deposition is performed, the present invention is not limited thereto. Deposition may be performed while the thin film deposition apparatus 100 is moved in the Y-axis direction, whereas the substrate 400 is fixed, or where both are moved.

Thus, in the thin film deposition apparatus 100 according to the current embodiment of the present invention, the patterning slit sheet 150 may be significantly smaller than a FMM used in a conventional deposition method. In other words, in the thin film deposition apparatus 100 according to the current embodiment of the present invention, deposition is continuously performed (i.e., in a scanning manner) while the substrate 400 is moved in the Y-axis direction. Thus, lengths of the patterning slit sheet 150 in the X-axis and Y-axis directions may be significantly less than the lengths of the substrate 400 in the X-axis and Y-axis directions. As described above, since the patterning slit sheet 150 may be formed to be significantly smaller than a FMM used in a conventional deposition method, it is relatively easy to manufacture the patterning slit sheet 150 used in embodiments of the present invention. In other words, using the patterning slit sheet 150, which is smaller than a FMM used in a conventional deposition method, is more convenient in all processes, including etching and subsequent other processes, such as precise extension, welding, moving, and cleaning processes, compared to the conventional deposition method using the larger FMM. This is more advantageous for a relatively large display device.

In order to perform deposition while the thin film deposition apparatus 100 or the substrate 400 is moved relative to each other as described above, the thin film deposition apparatus 100 and the substrate 400 may be separated from each other by a predetermined distance. This will be described later in detail.

The deposition source 110 contains and heats the deposition material 115. The deposition source 110 is disposed at side of the chamber that is opposite to a side at which the substrate 400 is disposed. As the deposition material 115 contained in the deposition source 110 is vaporized, the deposition material 115 is deposited on the substrate 400.

In particular, the deposition source 110 includes a crucible 111 and a heater 112. The crucible 111 is filled with the deposition material 115. The heater 112 heats the crucible 111 to vaporize the deposition material 115, which is contained in the crucible 111. The vaporized deposition material 115 moves towards a side of the crucible 111, and in particular, towards the deposition source nozzle unit 120.

The deposition source nozzle unit 120 is disposed at a side of the deposition source 110, and in particular, at the side of the deposition source 110 facing the substrate 400. In addition, the deposition source nozzle unit 120 includes a plurality of deposition source nozzles 121 arranged at equal intervals in the Y-axis direction (that is, the scanning direction of the substrate 400). The deposition material 115 that is vaporized in the deposition source 110 passes through the deposition source nozzles 121 of deposition source nozzle unit 120 towards the substrate 400. As described above, when the plurality of deposition source nozzles 121 are formed on the deposition source nozzle unit 120 in the Y-axis direction, a size of the pattern formed by the deposition material 115 that is discharged through each of patterning slits 151 in the patterning slit sheet 150 is only affected by the size of one deposition source nozzle 121. That is, it may be considered that one deposition nozzle 121 exists in the X-axis direction, and thus there is no shadow zone on the substrate 400. In addition, since the plurality of deposition source nozzles 121 are formed in the scanning

direction Y of the substrate 400, even if there is a difference between fluxes of the deposition source nozzles 121, the difference may be compensated and deposition uniformity may be maintained constantly.

5 The patterning slit sheet 150 is held in a frame 155. The patterning slit sheet 150 and the frame 155 are disposed between the deposition source 110 and the substrate 400. The frame 155 may be formed in a lattice shape, similar to a window frame, but the invention is not limited thereto. The patterning slit sheet 150 is bound inside the frame 155. The patterning slit sheet 150 includes a plurality of patterning slits 151 arranged in a row in the X-axis direction, with each slit 151 extending in the Y direction. The deposition material 115 that is vaporized in the deposition source 110, passes through the deposition source nozzle unit 120 and the patterning slit sheet 150 towards the substrate 400. The patterning slit sheet 150 may be manufactured by etching, which is the same method as used in a conventional method of manufacturing an FMM, and in particular, a striped FMM. Here, the total number of patterning slits 151 may be greater than the total number of deposition source nozzles 121, but the invention is not limited thereto.

10 In addition, the deposition source 110 (and the deposition source nozzle unit 120 coupled to the deposition source 110) and the patterning slit sheet 150 may be formed to be separated from each other by a predetermined distance. Alternatively, the deposition source 110 (and the deposition source nozzle unit 120 coupled to the deposition source 110) and the patterning slit sheet 150 may be connected by a connection member 135 as shown. That is, the deposition source 110, the deposition source nozzle unit 120, and the patterning slit sheet 150 may be formed integrally with each 15 other by being connected to each other via the connection member 135. The connection member 135 guides the deposition material 115, which is discharged through the deposition source nozzles 121, to move in the Z and Y directions and not to flow in the X-axis direction. In FIGS. 1 through 20 3, the connection members 135 are formed on left and right sides of the deposition source 110, the deposition source nozzle unit 120, and the patterning slit sheet 150 to guide the deposition material 115 not to flow in the X-axis direction. However, the present invention is not limited thereto. That is, the connection member 135 may be formed as a sealed type of a box shape to guide the flow of the deposition material 115 in the X-axis and Y-axis directions.

25 As described above, the thin film deposition apparatus 100 performs deposition while being moved relative to the substrate 400. In order to move the thin film deposition apparatus 100 relative to the substrate 400, the patterning slit sheet 150 is separated from the substrate 400 by a predetermined distance.

30 In particular, in a conventional deposition method using a FMM, deposition is performed with the FMM in close contact with a substrate in order to prevent formation of a shadow zone on the substrate. However, when the FMM is used in close contact with the substrate, the contact may cause defects. In addition, in the conventional deposition method, the size of the mask has to be the same as the size of the substrate since the mask cannot be moved relative to the substrate. Thus, the size of the mask has to be increased as display devices become larger. However, it is not easy to manufacture such a large mask.

35 In order to overcome this problem, in the thin film deposition apparatus 100 according to the current embodiment of the present invention, the patterning slit sheet 150 is disposed to be separated from the substrate 400 by a predetermined distance.

40 As described above, according to aspects of the present invention, a mask is formed to be smaller than a substrate, and deposition is performed while the mask is moved relative to the substrate. Thus, the mask can be easily

manufactured. In addition, defects caused due to the contact between a substrate and a FMM, which occurs in the conventional deposition method, may be prevented. In addition, since it is unnecessary to use the FMM in close contact with the substrate during a deposition process, the manufacturing speed may be improved.

FIG. 4 is a plan view of the patterning slit sheet 150 in the thin film deposition apparatus, according to an embodiment of the present invention. In the current embodiment of the present invention, a correction plate 157 is further disposed at a side of the patterning slit sheet 150. As shown there are two correction plates 157, but the invention is not limited thereto.

In particular, a thin film deposition apparatus of the current embodiment of the present invention shown in FIGS. 1 and 4 further includes the correction plate 157 in order to ensure uniformity of films formed on the substrate 400. In discharging an organic material (deposition material), the largest amount of organic material is discharged through a portion that is perpendicular to the deposition source nozzles 121 and the amount of discharged organic material is gradually reduced towards both ends of the patterning slit sheet 150 according to a cosine law. Thus, a deposition layer is likely to be formed having a bulgy center portion when the thin film deposition apparatus does not include the correction plate 157.

In order to make the thickness of the deposition layer less uneven, the correction plate 157 is disposed at each side of the patterning slit sheet 150. The correction plate 157 is formed on a surface of the patterning slit sheet 150 as a circular arc or a cosine curve. The correction plate 157 blocks some of the deposition material 115 discharged from the deposition source nozzles 121 towards the patterning slits 151. That is, since the deposition layer formed by the thin film deposition apparatus has a bulgy center portion, some of the deposition material discharged towards the center portion of the patterning slit sheet 150 has to be blocked in order to form the deposition layer of a uniform thickness. Therefore, the correction plate 157 is disposed on the way of the deposition material in order to block some of the deposition material. While shown as two correction plate 157, it is understood that the correction plate 157 can be a single plate having an opening which gradually widens as a function of distance from a center of the patterning slit sheet 150.

Here, since the correction plate 157 is formed to have the circular arc or the cosine curve shape, the deposition material discharged towards the center portion of the patterning slit sheet 150 is blocked more than the deposition material discharged towards left and right side portions of the patterning slit sheet 150. Then, the correction plate 157 may be disposed so that the thinnest part of the deposition layer (that is, parts of the deposition layer formed by the deposition material discharged through the both sides of the patterning slit sheet 150) becomes the entire thickness of the deposition layer.

As described above, since the correction plate 157 is disposed on the flowing path of the deposition material, the deposition layer formed by the thin film deposition apparatus 100 may be corrected. That is, a height of the correction plate 157 is increased in order to block more deposition material at the portion where a lot of deposition material is otherwise deposited, and the height of the correction plate 175 is reduced in order to block less deposition material at portions where less deposition material is deposited. Thus, the deposition amount of the deposition material may be adjusted so that the thickness of the deposition layer may be uniform.

According to the embodiment of the present invention shown in FIGS. 1 and 4, the uniformity of the thin film formed on the substrate 400 is within an error range of about

1 to about 2%, and thus, quality and reliability of the thin film deposition apparatus may be improved.

FIG. 5 is a plan view of a patterning slit sheet 150 in a thin film deposition apparatus according to another embodiment 5 of the present invention. In the current embodiment of the present invention, a length of patterning slit 151a located at a center portion of the patterning slit sheet 150 is less than those of patterning slits 151b located at both end portions of the patterning slit sheet 150 in order to ensure uniformity of the thin films formed on the substrate 400.

As described above, the deposition amount of the deposition material may be adjusted so that the thickness of the entire deposition layer may be constant by using the patterning slit sheet 150, in which the length of the patterning slit 151a at the center portion and the lengths of the patterning slits 151b at both ends of the patterning slit sheet 150 may be different from each other, like in the previous embodiment. In the thin film deposition apparatus 100 according to the current embodiment of the present invention shown in FIGS. 1 and 5, the uniformity of the thin film formed on the substrate 400 is within an error range of about 1 to about 2%. Thus, the quality and reliability of the thin film deposition apparatus 100 may be improved.

FIG. 6 is a perspective view of a thin film deposition apparatus 100 according to another embodiment of the present invention. Referring to FIG. 6, the thin film deposition apparatus 100 includes a deposition source 110, a deposition source nozzle unit 120, and a patterning slit sheet 150. In particular, the deposition source 110 includes a crucible 111 and a heater 112. The crucible 111 is filled with the deposition material 115. The heater 112 heats the crucible 111 to vaporize the deposition material 115, which is contained in the crucible 111. The vaporized deposition material 115 moves towards a side of the crucible 111, and in particular, towards the deposition source nozzle unit 120.

The deposition source nozzle unit 120 has a planar shape and is disposed at a side of the deposition source 110. The deposition source nozzle unit 120 includes a plurality of deposition source nozzles 121 arranged in the Y-axis direction. The patterning slit sheet 150 and a frame 155 are further disposed between the deposition source 110 and the substrate 400, and the patterning slit sheet 150 includes a plurality of patterning slits 151 arranged in the X-axis direction. The deposition source 110, the deposition source nozzle unit 120, and the patterning slit sheet 150 are connected to each other by the connection member 135.

The plurality of deposition source nozzles 121 formed on the deposition source nozzle unit 120 are tilted at a predetermined angle. In particular, the deposition source nozzles 121 may include deposition source nozzles 121a and 121b which are arranged in two rows, which are alternately arranged with each other. Here, the deposition source nozzles 121a and 121b may be tilted at a predetermined angle on an X-Z plane. However, the invention is not limited in relation to the number of rows of nozzles 121, and it is understood that the nozzles could also be further tilted in the Y-Z plane.

If the correction plate 157 of FIG. 4 is used or the lengths of the patterning slits 151 of FIG. 5, an efficiency of utilizing deposition material may be degraded because the deposition material is blocked by the correction plate 157 or the patterning slits 151. Therefore, in the current embodiment of the present invention shown in FIG. 6, the deposition source nozzles 121a and 121b are arranged in tilted states at a predetermined angle. Here, the deposition source nozzles 121a in a first row may be tilted toward the deposition nozzles 121b in a second row, and the deposition source nozzles 121b in the second row may be tilted toward the deposition source nozzles 121a in the first row. That is, the deposition source nozzles 121a arranged in the row at the

11

left side of the patterning slit sheet 150 are arranged to face the right side of the patterning slit sheet 150, and the deposition source nozzles 121b arranged in the row at the right side of the patterning slit sheet 150 are arranged to face the left side of the patterning slit sheet 150. While shown as having a same angle, it is understood that each row 121a, 121b need not have the same angle.

FIG. 7 is a graph showing a distribution of the deposition layer formed on the substrate 400 when the deposition source nozzles 121 are not tilted. FIG. 8 is a graph showing a distribution of the deposition layer formed on the substrate 400 when the deposition source nozzles 121 are tilted. When comparing the graphs of FIGS. 7 and 8 with each other, the deposition layer thickness formed on both end portions of the substrate 400 when the deposition source nozzles 121 are tilted is relatively greater than that of the deposition layer formed on the substrate 400 when the deposition source nozzles 121 are not tilted. Thus, the uniformity of the deposition layer is improved when the deposition source nozzles 121 are tilted. Therefore, the deposition amount of the deposition material may be adjusted so that a difference between the thicknesses of the deposition layer at the center portion and end portions of the substrate may be reduced and the entire thickness of the deposition layer may be constant. Moreover, the efficiency of utilizing the deposition material may be improved.

FIG. 9 is a schematic perspective view of the thin film deposition apparatus 100 according to another embodiment of the present invention. Referring to FIG. 9, the thin film deposition apparatus 100 includes a first deposition source 110, a first deposition source nozzle unit 120, a second deposition source 160, a second deposition source nozzle unit 170, and a patterning slit sheet 150. The patterning slit sheet 150 and a frame 155 are disposed between the first deposition source 110 and the second deposition source 160, and the substrate 400. The patterning slit sheet 150 includes a plurality of patterning slits 151 arranged in a row in the X-axis direction. In addition, the first deposition source 110, the second deposition source 160, the first deposition source nozzle unit 120, the second deposition source nozzle unit 170, and the patterning slit sheet 150 are connected to each other by the connection member 135.

In the thin film deposition apparatus 100, the first deposition source 110 contains a host material 115 and the second deposition source 160 contains a dopant material (not shown). As such, the host material 115 and the dopant material may be simultaneously deposited on the substrate 400. That is, since the host material 115 and the dopant material (not shown) are vaporized at different temperatures

12

from each other, the plurality of deposition sources 110 and 160 and the plurality of deposition source nozzle units 120 and 170 are provided to deposit the host material 115 and the dopant material at the same time.

Specifically, the first deposition source 110 and the second deposition source 160 contain and heat the deposition materials. The first deposition source 110 and the second deposition source 160 are disposed at a side of the chamber that is opposite to a side at which the substrate 400 is disposed. As the deposition materials contained in the first deposition source 110 and the second deposition source 160 are vaporized, the deposition materials are deposited on the substrate 400.

In particular, the first deposition source 110 includes a crucible 111 that is filled with the host material 115, and a heater 112. The heater 112 heats the crucible 111 to vaporize the host material 115. The vaporized host material 115 moves towards a side of the crucible 111, and in particular, towards the first deposition source nozzle unit 120. The second deposition source 160 includes a crucible 161 that is filled with the dopant material (not shown), and a heater (not shown). The heater (not shown) heats the crucible 161 to vaporize the dopant material (not shown). The vaporized dopant material (not shown) moves towards a side of the crucible 161, and in particular, towards the second deposition nozzle unit 170.

Examples of the host material may include tris(8-hydroxy-quinolinato)aluminum (Alq3), 9,10-di(naphth-2-yl)anthracene (AND), 3-tert-butyl-9,10-di(naphth-2-yl)anthracene (TBADN), 4,4'-bis(2,2-diphenyl-ethene-1-yl)-4,4'-dimethylphenyl (DPVBi), 4,4'-bis(2,2-diphenyl-ethene-1-yl)-4,4'-dimethylphenyl (p-DMDPVBi), tert(9,9-diarylfluorene)s (TDAF), 2-(9,9'-spirobifluorene-2-yl)-9,9'-spirobifluorene (BSDF), 2,7-bis(9,9'-spirobifluorene-2-yl)-9,9'-spirobifluorene (TSDF), bis(9,9-diarylfluorene)s (BDAF), 4,4'-bis(2,2-diphenyl-ethene-1-yl)-4,4'-di-(tert-butyl)phenyl (p-TDPVBi), 1,3-bis(carbazol-9-yl)benzene (mCP), 1,3,5-tris(carbazol-9-yl)benzene (tCP), 4,4',4"-tris(carbazol-9-yl)triphenylamine (TcTa), 4,4'-bis(carbazol-9-yl)biphenyl (CBP), 4,4'-bis(9-carbazolyl)-2,2'-dimethyl-biphenyl (CBDP), 4,4'-bis(carbazol-9-yl)-9,9-dimethyl-fluorene (DMFL-CBP), 4,4'-bis(carbazol-9-yl)-9,9-bis(9-phenyl-9H-carbazol)fluorene (FL-4CBP), 4,4'-bis(carbazol-9-yl)-9,9-di-tolyl-fluorene (DPFL-CBP), 9,9-bis(9-phenyl-9H-carbazol)fluorene (FL-2CBP), etc.

Examples of the dopant material may include DPABVi (4,4'-bis[4-(di-p-tolylamino)styryl]biphenyl), ADN (9,10-di(naph-2-yl)anthracene), TBADN (3-tert-butyl-9,10-di(naph-2-yl)anthracene), etc.

DPABVi

13

-continued

14

As described above, the thin film deposition apparatus 100 is characterized in that the first deposition source 110 contains the host material 115 and the second deposition source 160 contains the dopant material (not shown). The first deposition source 110 and the second deposition source 160 are provided so that the host material 115 and the dopant material are simultaneously deposited on the substrate 400. Since the host material 115 and the dopant material may be simultaneously deposited on the substrate 400, the deposition process may be simplified and performed rapidly, which improves the efficiency of the thin film deposition apparatus 100.

FIG. 10 is a schematic perspective view of a thin film deposition apparatus 100 according to another embodiment of the present invention. Referring to FIG. 10, the thin film deposition apparatus 100 includes a first deposition source 110, a first deposition source nozzle unit 120, a second deposition source 160, a second deposition source nozzle unit 170, and a patterning slit sheet 150. The patterning slit sheet 150 and a frame 155 are disposed between the first and second deposition sources 110 and 160 and the substrate 400. The patterning slit sheet 150 includes a plurality of patterning slits 151 arranged in a row in the X-axis direction. In addition, the first and second deposition sources 110 and 160, the first and second deposition source nozzle units 120 and 170, and the patterning slit sheet 150 are connected to each other by the connection member 135. In the thin film deposition apparatus 100, the first deposition source 110 contains a host material 115 and the second deposition source 160 contains a dopant material (not shown) so that the host material 115 and the dopant material may be simultaneously deposited on the substrate 400.

The thin film deposition apparatus 100 is different from that of the previous embodiments shown in FIG. 9 in that a plurality of deposition source nozzles 121' and 171' are respectively formed on the first and second deposition source nozzle units 120 and 170. The deposition source nozzles 121' and 171' are tilted at a predetermined angle. That is, the deposition source nozzles 121' and 171' are tilted at a predetermined angle on a Y-Z plane.

Although a content of the dopant material may vary depending on the material forming thin films, the dopant material may be contained by about 3 to about 20 parts by weight in the thin film forming material (total weight of the host and dopant materials) of 100 parts by weight. If the content of the dopant material exceeds the above described range, the light emitting property of an organic light emitting display device may be degraded. However, when the deposition source nozzles 121 and 171 are arranged in parallel with a Z-axis like in the previous embodiment described

with reference to FIG. 9, the dopant material is deposited on the substrate 400 at an initial stage of the deposition process, the dopant material and the host material are alternatively deposited on the substrate 400 at an intermediate stage of the deposition process, and the host material is deposited on the substrate 400 at a rear stage of the deposition process. That is, mixture ratios of the host material and the dopant material may vary depending on regions of the substrate 400.

Thus, in the thin film deposition apparatus 100 according to the current embodiment of the present invention shown in FIG. 10, the deposition source nozzles 121' and 171' are tilted at a predetermined angle. The deposition source nozzles 121' of the first deposition source nozzle unit 120 and the deposition source nozzles 171' of the second deposition source nozzle unit 170 may be tilted to face each other. That is, the deposition source nozzles 121' of the first deposition source nozzle unit 120 may be tilted to face the second deposition source 170, and the deposition source nozzles 171' of the second deposition source nozzle unit 170 may be tilted to face the first deposition source 120.

Through the above described structure, the mixing ratio of the host material 115 and the dopant material in the deposition material may be constant throughout the entire substrate 400. In addition, if the thin films are formed by using the mixture in which the host material 115 and the dopant material are mixed with a constant mixture ratio, the thin films may represent improved characteristics in view of color coordinate, optical efficiency, driving voltage, and lifespan.

FIG. 11 is a schematic perspective view of a thin film deposition apparatus 100 according to another embodiment of the present invention. Referring to FIG. 11, the thin film deposition apparatus 100 includes a first deposition source 110, a first deposition source nozzle unit 120, a second deposition source 180, a second deposition source nozzle 181, and a patterning slit sheet 150. The patterning slit sheet 150 and a frame 155 are disposed between the first and second deposition sources 110 and 180 and the substrate 400. The patterning slit sheet 150 includes a plurality of patterning slits 151 arranged in the X-axis direction. In addition, the first and second deposition sources 110 and 180, the first deposition source nozzle unit 120 and the second deposition source nozzle 181, and the patterning slit sheet 150 are connected to each other by the connection member 135. The first deposition source 110 contains a host material 115. The second deposition source 180 contains a dopant material (not shown) so that the host material 115 and the dopant material may be simultaneously deposited on the substrate 400.

The thin film deposition apparatus 100 shown in FIG. 11 is different from the thin film deposition apparatus 100 shown in FIG. 9 in that the second deposition source 180 is a point source, not a linear source. As described above, the dopant material may be contained by about 3 to about 20 parts by weight in the thin film forming material (total weight of the host and dopant materials) of 100 parts of weight. That is, since the dopant material is relatively less than the host material in the thin film forming material, it is not necessary to use the linear source having a large capacity for containing the dopant material. Thus, in the thin film deposition apparatus 100 shown in FIG. 11, the first deposition source 110 containing the host material is formed as the linear source, and the second deposition source 180 containing the dopant material is formed as the point source.

Here, although the second deposition source 180 (that is, a point source) is disposed in FIG. 11, the present invention is not limited thereto. That is, a plurality of second deposition sources may be provided according to the content amount of the dopant material that is needed.

As described above, since the second deposition source 180 is formed as the point source, the thin film deposition apparatus 100 may have a simple structure and fabrication costs of the thin film deposition apparatus 100 may be reduced.

FIG. 12 is a schematic perspective view of a thin film deposition apparatus 100 according to another embodiment of the present invention. Referring to FIG. 12, the thin film deposition apparatus 100 includes a first deposition source 190, a first deposition source nozzle 191, a second deposition source 180, a second deposition source nozzle 181, and a patterning slit sheet 150. The patterning slit sheet 150 and a frame 155 are disposed between the first and second deposition sources 190 and 180 and the substrate 400. The patterning slit sheet 150 includes a plurality of patterning slits 151 arranged in the X-axis direction. In addition, the first and second deposition sources 190 and 180 and the deposition source nozzles 181 and 191 are accommodated in a deposition source accommodation unit 195. The deposition source accommodation unit 195 and the patterning slit sheet 150 are connected to each other by the connection member 135. In the thin film deposition apparatus 100, the first deposition source 190 contains a host material (not shown) and the second deposition source 180 contains a dopant material (not shown) so that the host material and the dopant material may be simultaneously deposited on the substrate 400.

The thin film deposition apparatus 100 shown in FIG. 12 is different from the thin film deposition apparatus 100 shown in FIG. 11 in that the first deposition source 190 is a point source, not a linear source. In particular, as a distance between the deposition sources 180 and 190 and the substrate 400 is increased, the point source may be more favorable for performing the deposition than the linear source. Therefore, the first deposition source 190 containing the host material and the first deposition source nozzles 191 may be formed as a plurality of point sources. In particular, the first deposition source 190 on which the first deposition source nozzles 191 are formed may be formed as a revolver. As described above, since the first and second deposition sources 190 and 180 are formed as the point sources, the thin film deposition apparatus 100 may have a simple structure and fabrication costs of the thin film deposition apparatus 100 may be reduced.

FIG. 13 is a schematic perspective view of a thin film deposition assembly 1000 according to another embodiment of the present invention. Referring to FIG. 13, the thin film

deposition assembly 1000 includes a plurality of thin film deposition apparatuses 100, 200, 300. Each of the thin film deposition apparatuses 100, 200, 300 has the structure like that of the thin film deposition apparatus 100 illustrated in FIGS. 1 through 3. In other words, the thin film deposition assembly 1000 includes a multi-deposition source that simultaneously discharges deposition materials for forming the R emission layer, the G emission layer, and the B emission layer.

10 In particular, the thin film deposition assembly 1000 includes a first thin film deposition apparatus 100, a second thin film deposition apparatus 200, and a third thin film deposition apparatus 300. Each of the first thin film deposition apparatus 100, the second thin film deposition apparatus 200, and the third thin film deposition apparatus 300 has the same structure as the thin film deposition apparatus 100 described with reference to FIGS. 1 through 3, and thus a detailed description thereof will not be provided here.

15 The deposition sources 110 of the first thin film deposition apparatus 100, the second thin film deposition apparatus 200 and the third thin film deposition apparatus 300 may contain different deposition materials, respectively. The first thin film deposition apparatus 100 may contain a deposition material for forming a R emission layer, the second thin film deposition apparatus 200 may contain a deposition material for forming a G emission layer, and the third thin film deposition apparatus 300 may contain a deposition material for forming a B emission layer.

20 In other words, in a conventional method of manufacturing an organic light-emitting display device, a separate chamber and mask are used to form each color emission layer. However, when the thin film deposition assembly 1000 according to the current embodiment of the present invention is used, the R emission layer, the G emission layer and the B emission layer may be formed at the same time with a single multi-deposition source. Thus, the time it takes to manufacture the organic light-emitting display device is sharply reduced. In addition, the organic light-emitting display device may be manufactured with less chambers, so that equipment costs are also markedly reduced.

25 A patterning slit sheet 150 of the first thin film deposition apparatus 100, a patterning slit sheet 250 of the second thin film deposition apparatus 200, a patterning slit sheet 350 of the third thin film deposition apparatus 300 may be arranged to be offset by a constant distance with respect to each other, in order for deposition regions corresponding to the patterning slit sheets 150, 250 and 350 not to overlap on the substrate 400. In other words, when the first thin film deposition apparatus 100, the second thin film deposition apparatus 200, and the third thin film deposition apparatus 300 are used to deposit a R emission layer, a G emission layer and a B emission layer, respectively, patterning slits 151 of the first thin film deposition apparatus 100, patterning slits 251 of the second thin film deposition apparatus 200, and patterning slits 351 of the third thin film deposition apparatus 300 are arranged not to be aligned with respect to each other, in order to form the R emission layer, the G emission layer and the B emission layer in different regions of the substrate 400.

30 In addition, the deposition materials for forming the R emission layer, the G emission layer, and the B emission layer may have different deposition temperatures. Therefore, the temperatures of the deposition sources of the respective first, second, and third thin film deposition apparatuses 100, 200, and 300 may be set to be different.

35 Although the thin film deposition assembly 1000 according to the current embodiment of the present invention

includes three thin film deposition apparatuses 100, 200, 300, the present invention is not limited thereto. In other words, a thin film deposition assembly according to another embodiment of the present invention may include a plurality of thin film deposition apparatuses, each of which contains a different deposition material. For example, a thin film deposition assembly according to another embodiment of the present invention may include five thin film deposition apparatuses respectively containing materials for a R emission layer, a G emission layer, a B emission layer, an auxiliary layer (R') of the R emission layer, and an auxiliary layer (G') of the G emission layer.

As described above, a plurality of thin films may be formed at the same time with a plurality of thin film deposition apparatuses, and thus manufacturing yield and deposition efficiency are improved. In addition, the overall manufacturing process is simplified, and the manufacturing costs are reduced.

FIG. 14 is a cross-sectional view of an active matrix type organic light emitting display device fabricated by using a thin film deposition apparatus, according to an embodiment of the present invention. Referring to FIG. 14, a buffer layer 51 is formed on a substrate 50 formed of glass or plastic. A thin film transistor (TFT) and an organic light emitting display device (OLED) are formed on the buffer layer 51.

An active layer 52 having a predetermined pattern is formed on the buffer layer 51. A gate insulating layer 53 is formed on the active layer 52. A gate electrode 54 is formed in a predetermined region of the gate insulating layer 53. The gate electrode 54 is connected to a gate line (not shown) that applies a TFT ON/OFF signal. An interlayer insulating layer 55 is formed on the gate electrode 54. Source/drain electrodes 56 and 57 are formed such as to contact source/drain regions 52a and 52c, respectively, of the active layer 52 through contact holes. A passivation layer 58 is formed of SiO_2 , SiN_x , etc. on the source/drain electrodes 56 and 57. A planarization layer 59 is formed of an organic material, such as acryl, polyimide, benzocyclobutene (BCB), etc., on the passivation layer 58. A pixel electrode 61, which functions as an anode of the OLED, is formed on the planarization layer 59. A pixel defining layer 60 formed of an organic material covers the pixel electrode 61. An opening is formed in the pixel defining layer 60, and an organic layer 62 is formed on a surface of the pixel defining layer 60 and on a surface of the pixel electrode 61 exposed through the opening. The organic layer 62 includes an emission layer. The present invention is not limited to the structure of the organic light-emitting display device described above, and various structures of organic light-emitting display devices may be applied to the present invention.

The OLED displays predetermined image information by emitting red, green and blue light as current flows. The OLED includes the pixel electrode 61, a counter electrode 63, and the organic layer 62. The pixel electrode 61 is connected to the drain electrode 56 of the TFT and to which a positive power voltage is applied. The counter electrode 63 is formed so as to cover the entire sub-pixel and to which a negative power voltage is applied. The organic layer 62 is disposed between the pixel electrode 61 and the counter electrode 63 to emit light. The pixel electrode 61 and the counter electrode 63 are insulated from each other by the organic layer 62, and respectively apply voltages of opposite polarities to the organic layer 62 to induce light emission in the organic layer 62.

The organic layer 62 may include a low-molecular weight organic layer or a high-molecular weight organic layer. When a low-molecular weight organic layer is used as the

organic layer 62, the organic layer 62 may have a single or multi-layer structure including at least one selected from the group consisting of a hole injection layer (HIL), a hole transport layer (HTL), an emission layer (EML), an electron transport layer (ETL), an electron injection layer (EIL), etc. Examples of available organic materials include copper phthalocyanine (CuPc), N,N'-di(naphthalene-1-yl)-N,N'-diphenyl-benzidine (NPB), tris-8-hydroxyquinoline aluminum (Alq3), or the like. The low-molecular weight organic layer may be formed by vacuum deposition.

When a high-molecular weight organic layer is used as the organic layer 62, the organic layer 62 may mostly have a structure including a HTL and an EML. In this case, the HTL may be formed of poly(ethylenedioxythiophene) (PEDOT), and the EML may be formed of polyphenylenevinylene (PPVs) or polyfluorenes. The HTL and the EML may be formed by screen printing, inkjet printing, or the like.

The organic layer 62 is not limited to the organic layers described above, and may be embodied in various ways.

The pixel electrode 61 functions as an anode, and the counter electrode 63 functions as a cathode. Alternatively, the pixel electrode 61 may function as a cathode, and the counter electrode 63 may function as an anode.

The pixel electrode 61 may be formed as a transparent electrode or a reflective electrode. Such a transparent electrode may be formed of indium tin oxide (ITO), indium zinc oxide (IZO), zinc oxide (ZnO), or indium oxide (In_2O_3). Such a reflective electrode may be formed by forming a reflective layer from silver (Ag), magnesium (Mg), aluminum (Al), platinum (Pt), palladium (Pd), gold (Au), nickel (Ni), neodymium (Nd), iridium (Ir), chromium (Cr) or a compound thereof and forming a layer of ITO, IZO, ZnO, or In_2O_3 on the reflective layer.

The counter electrode 63 may be formed as a transparent electrode or a reflective electrode. When the counter electrode 63 is formed as a transparent electrode, the counter electrode 63 functions as a cathode. To this end, such a transparent electrode may be formed by depositing a metal having a low work function, such as lithium (Li), calcium (Ca), lithium fluoride/calcium (LiF/Ca), lithium fluoride/aluminum (LiF/Al), aluminum (Al), silver (Ag), magnesium (Mg), or a compound thereof on a surface of the organic layer 62 and forming an auxiliary electrode layer or a bus electrode line thereon from a transparent electrode forming material, such as ITO, IZO, ZnO, In_2O_3 , or the like. When the counter electrode 63 is formed as a reflective electrode, the reflective layer may be formed by depositing Li, Ca, LiF/Ca, LiF/Al, Al, Ag, Mg, or a compound thereof on the entire surface of the organic layer 62.

In the organic light-emitting display apparatus described above, the organic layer 62 including the emission layer may be formed by using a thin film deposition apparatus 100 (refer to FIG. 1), which is described above. The thin film deposition apparatuses according to the embodiments of the present invention described above may be applied to form an organic layer or an inorganic layer of an organic TFT, and to form layers from various materials.

As described above, the thin film deposition apparatus 60 according to aspects of the present invention may be easily manufactured and may be simply applied to produce large-sized display devices on a mass scale. The thin film deposition apparatus may improve manufacturing yield and deposition efficiency.

Although a few embodiments of the present invention have been shown and described, it would be appreciated by those skilled in the art that changes may be made in this

19

embodiment without departing from the principles and spirit of the invention, the scope of which is defined in the claims and their equivalents.

What is claimed is:

1. A thin film deposition apparatus for forming a thin film on a substrate, the apparatus comprising:
  - a deposition source that discharges a deposition material;
  - a deposition source nozzle unit disposed at a side of the deposition source and including a plurality of deposition source nozzles arranged in a first direction;
  - a patterning slit sheet disposed opposite to the deposition source nozzle unit and including a plurality of patterning slits arranged in a row in a second direction that is perpendicular to the first direction;
  - a frame in which the patterning slit sheet is disposed; and
  - a connection member which connects the deposition source, the deposition source nozzle unit, and the frame, the connection member extending at an oblique angle from a region of the deposition source nozzle unit that is spaced apart from the plurality of deposition

source nozzles in the second direction to a region of the patterning slit sheet that is spaced apart from the plurality of patterning slits in the second direction, wherein a deposition is performed while one of the substrate and the thin film deposition apparatus moves relative to the other one of the substrate and the thin film deposition apparatus in the first direction, wherein the plurality of deposition source nozzles protrude from an upper surface of the deposition source nozzle unit toward the patterning slit sheet, wherein the connecting member is connected to an edge of the deposition source nozzle unit and an edge of the frame, and wherein each of the patterning slits is elongated in the first direction so as to overlap the plurality of deposition source nozzles.

2. The thin film deposition apparatus of claim 1, wherein the connection member directly contacts the deposition source nozzle unit.
